Primary Examiner — George D. Kirschbaum*Assistant Examiner* — Jasmine L. Coleman(74) *Attorney, Agent, or Firm* — Leason Ellis LLP(57) **CLAIM**

The ornamental design for a drive thru structure, as shown and described.

DESCRIPTION

FIG. 1 is front perspective view of a drive thru structure according to our new design;

FIG. 2 is a left side perspective view thereof;

FIG. 3 is a rear perspective view thereof; and,

FIG. 4 is an enlarged detail view taken from portion 4 in FIG. 3.

The dash-dot-dash broken line defines a boundary of the claimed design and is not an ornamental part of the design itself. The dash-dash broken-lines showing are included for the purpose of illustrating environmental structure and form no part of the claimed design.
